CLAIM

The ornamental design for a device for elevating the lenses of eyeglasses, substantially as shown and described.

DESCRIPTION

FIG. 1 is an elevational view showing the rear of a device for elevating the lenses of eyeglasses embodying my new design, the eyeglasses being shown in broken lines for illustrative purposes only;

FIG. 2 is an enlarged isometric view showing the front of the device, namely the side which is remote from the face of the wearer when the device is in operating position;

FIG. 3 is an enlarged side elevational view showing the device as seen from the left in FIG. 1; and

FIG. 4 is an enlarged top plan view.

FIG. 1.FIG. 2.FIG. 3.FIG. 4.
